DESIGN FOR A FOUNDATION GARMENT

Katherine K. Smythe, Evanston, Ill.

Application February 24, 1941, Serial No. 99,180

Term of patent 14 years

To all whom it may concern:

Be it known that I, Katherine K. Smythe, a citizen of the United States, residing at 802 Madison Street, Evanston, in the county of Cook and State of Illinois, have invented a new, original, and ornamental Design for a Foundation Garment, of which the following is a specification, reference being had to the accompanying drawing, forming part thereof.

I claim:

The ornamental design for a foundation garment, substantially as shown.

KATHERINE K. SMYTHE.
